UNITED STATES PATENT AND TRADEMARK OFFICE
CERTIFICATE OF CORRECTION

PATENT NO. : D863,677 S
APPLICATION NO. : 35/504776
DATED : October 15, 2019
INVENTOR(S) : Kyungil Chung et al.

Page 1 of 1

It is certified that error appears in the above-identified patent and that said Letters Patent is hereby corrected as shown below:

On the Title Page

Item (72) should read:

-- (72) Inventors: **Kyungil Chung**, Dublin (IE); **Florent Cuchet**, Stockholm (SE) --

Signed and Sealed this
Tenth Day of December, 2019

Andrei Iancu
Director of the United States Patent and Trademark Office
